HOSIERY AND METHOD OF MAKING SAME

Application filed July 10, 1931. Serial No. 550,010.

The invention relates to a novel form of knit stockings and to the method of making the same, and is more particularly directed to the knitting of full fashioned hosiery provided with a turned welt at the top connected to the body portion by an initial loose course and a final picot course, comprising alternate loops displaced laterally the distance of one loop to form an anti-ravel or non-run course.

5 The invention is illustrated in the accompanying drawing, which is a magnified section of the fabric at the junction of the welt and the body portion of the stocking.

10 Referring to the drawing, B indicates the body portion of the stocking, which may be a plain knit fabric consisting of regular courses 5. The welt is indicated, as a whole, by the reference W, W' denoting the back of the welt and W² the front thereof. The initial course of the welt is a loose course 1, which is succeeded by the necessary number 15 of plain courses 2 to form the back and a similar series of plain courses 3 forming the front of the welt, the final course 4 of the 20 welt being a picot course having double loops 25 engaging alternate pairs of loops 5 in the first course of the body B and single loops connecting successive loops 3 of the welt, the sinker loops of the loose course 1 being knit 30 into the first course 5 of the body B, the junction 35 of the welt and body formed by the loose course 1 and the picot course 4 producing an open work effect, which may be pleasingly enhanced by making the picot course of thread of different color from that used in the other courses.

The fabric may be knit on any of the standard straight machines provided with a picot bar and in operation the first course 1 of the 40 welt section is formed in the usual manner by bringing the loose course mechanism into operation, the object of said loose course being to facilitate the turning of the welt and the joining of the welt with the body portion 45 of the fabric.

The desired number of plain or regular courses is then knit, determined by the length of the welt, the final course being a loose course, which is converted into a picot 50 course by bringing the picot bar into action,

after which the welt is turned by the regular operation of the welt bar mechanism, which is followed by the transfer of the loops or stitches on the welt bar to the needles and the initial plain course 5 of the body portion B is formed and followed by the desired number of such plain courses.

55 As a typical example of forming the welt and uniting the same to the body portion, there are knit 120 courses, the first being a loose course, constituting the back of the welt, followed by 8 courses which form the top of the stocking, and continuing with 120 courses constituting the front of the welt. 60 After finishing the 119th course of the last series, the 120th is formed as a loose course and the picot bar is brought into operation, said bar carrying points which transfer alternate loops or stitches to intermediate needles, so that there are two loops or stitches on 65 every other needle and no loops on intervening needles. When this operation is completed, the welt is turned by the welt bar, which transfers the loops to needles, so that alternate needles carry one and three loops, 70 respectively, in the order indicated in the drawing. The machine is then operated to run the first course 5 of the body portion B, so that the initial loose course 1 of the welt is knit into the course 5 in regular order and the picot course 4 is inter-knit with the last plain course of the welt and the first course 75 of the body in the manner and form shown.

80 It will be noted that, by this method, the transferred loops will extend directly from the needle loops of the previously knit course to their next adjacent loops between the next adjacent loops and their respective incident loops of the first knit course. Thus the transferred loops will not pass through the first 85 knit course and around the inside face of the welt to be entangled with loops of the first knit course, but instead will lie entirely on the same side of the first knit course as the last knit course.

90 It will be understood that the so-called plain or regular courses may be of any desired type usually employed in fabricating articles of this character; that is to say, the body of the fabric may be made in accordance with 95 100

any of the standard modes of knitting designed to produce plain, ribbed, lace and similar fabrics with or without color schemes or variations, such as stripes or geometrical 5 patterns, produced by the usual standard practice. The term plain or regular as applied to the fabric is, therefore, to be interpreted as applying to and indicating the normal or typical form of knitting employed 10 in those portions of the fabric other than the loose and picot courses constituting the connection between the turned welt and the body portion.

What we claim is:

15 1. The method of knitting a turned welt which comprises knitting the first course of the welt, knitting successive courses of the welt fabric, knitting the last course of the welt, transferring alternate loops of the last 20 course laterally to put them together with their respective neighboring loops, thereafter turning the welt by putting loops of the first course of the welt together with loops of the last course and thereafter drawing loops of 25 the first course of the leg fabric through the loops of the first and last courses of the welt fabric and then continuing the knitting of the leg fabric.

2. The method of knitting a turned welt 30 which comprises knitting the first course of the welt with elongated loops, knitting successive courses of the welt fabric, knitting the last course of the welt with elongated loops, transferring alternate loops of the last 35 course laterally to put them together with their respective neighboring loops, thereafter turning the welt by putting loops of the first course of the welt together with loops of the last course and thereafter drawing loops of 40 the first course of the leg fabric through the loops of the first and last courses of the welt fabric and then continuing the knitting of the leg fabric.

3. A welt fabric structure comprising a 45 length of knitted fabric folded upon itself to form two ply fabric with the terminal courses of the length of fabric together and incident loops of the respective courses joined by a course of fabric continuous with the welt fabric, one terminal course being a transfer 50 course and comprising alternate loops displaced laterally to be, together with their respective next adjacent loops, joined to the loops of other terminal courses incident to the 55 next adjacent loops, the displaced loops of the terminal transfer course being entirely on the same side of the other terminal course as the transfer course.

4. A welt fabric structure comprising a 60 length of knitted fabric folded upon itself to form two ply fabric with the terminal courses of the length of fabric together and incident loops of the respective courses joined by a course of fabric continuous with the 65 welt fabric, the terminal courses consisting of

elongated loops, one terminal course being a transfer course and comprising alternate loops displaced laterally to be, together with their respective next adjacent loops, joined to the loops of other terminal courses incident to the next adjacent loops, the displaced loops of the terminal transfer course being entirely on the same side of the other terminal course as the transfer course.

5. A full fashioned stocking welt, comprising a length of fabric folded on itself with the first and last knit courses together, the last knit course comprising alternate loops transferred to their next adjacent loops and together therewith joined respectively to the loops of the first knit course incident to the mentioned next adjacent loops, the transferred loops being entirely on the same side of the first knit course as the last knit course.

In testimony whereof we affix our signatures.

ALBERT E. MARGERISON.
CARL R. HAHN.
